UNITED STATES PATENT OFFICE

EUGENIO GALIZI AND ANDRIANO GALIZI, OF NEW YORK, N. Y.

PITCH SLIDER MECHANISM

Application filed July 24, 1928. Serial No. 294,994.

This invention relates to improvements in accordions and has for its object to provide a pitch slide mechanism constructed and arranged for operation in conjunction with a standard keyboard.

One of the objects of our invention is to provide a pitch slide mechanism attachable to the accordion casing and at the front edge of the keyboard so that the player or artist 10 may vary the pitch at any position on the scale and without interrupting the finger movement on the keys.

More specifically our invention relates to a pitch slider mechanism positioned within the 15 accordion case and operable by the thumb or palm of the hand from any position on the keyboard, said mechanism being attachable as a unit to any conventional type of accordion.

20 To enable others skilled in the art to more fully comprehend the underlying features of our invention and its practical application to the particular instrument in which it is employed, reference is had to the accompanying 25 drawings wherein

Fig. 1 is a top plan of a preferred form of a pitch slider mechanism embodying our invention.

Fig. 2 is a top plan of a modified form of 30 our invention.

Fig. 3 is a detail view of a guide plate.

Fig. 4 is a partial perspective view of an 35 accordion key board and the presser bar.

Fig. 5 is a bottom plan showing the valve 40 board and its relation to the slider mechanism.

Fig. 6 is an end view.

Referring now to the drawings wherein like reference characters designate corresponding parts throughout the several views, and referring particularly to Figs. 4 and 5, the accordion case or frame 5 is provided with the usual valve board 6. The key valves cooperate with a pitch slider 7 constructed 45 and arranged to be shifted relative to the valve openings so as to produce a high or low pitch. This construction is common and well known in the conventional type of accordion and to which our invention is applicable.

It has heretofore been the practice to provide a knob or lever for actuating the pitch slider preferably intermediate the ends of the key board case. This construction and practice is objectionable for the reason that in 55 playing the very high or very low keys at each end of the keyboard, it is necessary for the artist to remove his hand from the keyboard, to actuate the knob or lever resulting in limitations in tone and volume while playing 60 very difficult selections.

Our invention therefore aims to provide a pitch slider mechanism in which the slider may be actuated without removing the hand from the keyboard at any point on the scale. 65 To that end, in the preferred form of the invention, and as shown by Fig. 1, we provide a flat plate 8 secured to the bottom 9 of the keyboard case 10 positioned at a point substantially intermediate the sides 11, 12 of the case and the sharp and flat keys 13, 14. The front edge 15 of the keyboard case is partially cut away as at 16 and attached to this portion of the key board is a top flat bar 17 preferably formed integral with the plate 8 70 and fastened to the keyboard by screws 18.

Hingedly connected to the top flat bar 17 by spring hinges 19 is an elongated presser bar 20 substantially L-shaped in cross-section and of such a length as to extend in proximity to the highest and lowest octave on the keyboard whereby said presser bar may be actuated by the thumb or palm without removing the hand from the finger board.

The presser bar 20 is connected to a pin or post 21 by a wire link 22, one end of said link being bent and retained in an eye 23 of the presser bar and the opposite end of the link passing through an aperture in the upper end of the pin or post. The pin or post is 85 slideable in a suitable guide 24 and is provided with a stop pin 25 engaging the guide thus limiting the return movement of the pin when pressure on the hinges 19 of the presser bar 20 is released.

The lower bevelled end 26 of the pin or post is adapted to register with the notches 27, 28 of a pair of angularly disposed levers 29, 30, the upper ends of which are substantially 90 parallel with sliding pin or post and form a 95

guide for the beveled end to enter the notches of either of said levers. Springs 31, 32 secured to suitable screw heads 33, 34 are adapted to urge the levers toward each other, said springs having their lower ends fastened as at 35, 35^a and their upper ends retained in suitable eyes 36 formed with the levers.

The lower ends of the levers 29, 30 are pivotally connected as at 37, 38 to the outer ends of a rocker arm 39 pivoted as at 40 to the bottom of the plate 8. The depending extension 41 of the rocker arm is formed with side flanges 42 which form a guide for an adjusting plate 43, the lower slotted end 44 of which is bent at right angles thereto and adapted to be locked by a screw 45 in its adjusted position when connected to the tooth 46 of a lug 47 as shown in Fig. 3.

The lug is permanently fastened as at 48 to a sectional rod 49 slidable through a plate guide 50 fastened to the rear of the valve board, as shown by Fig. 5. The outer end 51 of the rod 49 is connected to a crank rod 52 rotatable in suitable bearings 53, said crank rod being in turn fastened to the pitch slider 7.

From the above description taken in connection with the drawings, it will be seen that when the presser bar is actuated and the pin or post 21 is depressed into the right hand or left hand lever, the rocker arm will be partly rotated on its pivot either to the left or to the right. This movement shifts the slide rod 49, 51, with the result that the crank rod operates the pitch slider. In order to limit the movement of the Y-shaped rocker arm, stop pins 54, 55 are provided on the plate 8. When one of the levers is actuated by the pin or post, the notch is moved below the notch of the opposite lever and since the springs of the presser bar draws the post or pin back to its normal position upon each actuation, when the post or pin is depressed again, it actuates the opposite lever with the result that the pitch slider may be moved back and forward to give the desired pitch.

In the form of the invention shown by Fig. 2, the presser bar 56 is similarly connected by a link 57 to a sliding plate 58 operable in a suitable guide 59. Pivotally connected as at 60 to the lower end of said plate, is a rocker 61 having notched arms 62, 63 adapted to engage the curved arms 64, 65 of a lever 66 pivotally connected as at 67 to the lower end 68 of an extension to the above mentioned plate. The lower end of the lever 66 is adapted to be locked to the tooth of the lug as shown in Fig. 3. A spring 69 engaging the sides of the rocker 61 maintains the same in its normal straight position and upon each depression of said member causes either of the arms 64, 65 to be engaged with the result that as the lever 66 is rocked on its pivot, the lug is shifted laterally whereupon the slide rod and crank rod actuates the pitch

slider in the same manner as described in connection with Fig. 1.

While we have shown and described our invention with some degree of particularity, it will be realized that other modifications and changes may be resorted to under special conditions. We therefore do not wish to be limited and restricted to the exact details shown and described, but reserve the right to make such changes and modifications as may fairly fall within the scope of the subject matter now being claimed.

Having shown and described my invention, what I claim as new and desire to secure by Letters Patent is:—

1. In an accordion having a pitch slider, a presser bar attached to the front edge of the keyboard case of said accordion, a rocker arm connected to said slider and means operable by said presser bar for actuating said rocker arm whereby the slider may be shifted.

2. In an accordion having a pitch slider, a spring hinged presser bar attached to the bottom and at front edge of the keyboard case of said accordion, a rocker arm connected to said slider and means operable by said presser bar for actuating said rocker arm whereby the slider may be shifted.

3. In an accordion having a pitch slider, a presser bar attached to the bottom and at the front edge of the keyboard case, said bar being of a length for engagement by the thumb or palm from any point on the keyboard scale, a rocker arm connected to said slider and means operable by said presser bar for actuating said rocker arm whereby the slider may be shifted.

4. In an accordion having a pitch slider, a plate attached to the bottom of the keyboard case, a presser bar hinged to said plate at the front edge of the keyboard case, a rocker arm connected to said plate and slider and means operable by said presser bar for actuating said rocker arm whereby the slider may be shifted.

5. In an accordion having a pitch slider, a plate attached to the bottom of the keyboard case, a plate bar hinged to said plate at the front edge of the keyboard case, a rocker arm fastened to said slider, a pair of levers for rocking said rocker arm and means operable by the presser bar for actuating said levers and rocker arm whereby the slider may be shifted.

6. In an accordion having a pitch slider, a plate attached to the bottom of the keyboard case, a presser bar hinged to the top of the plate and located at the front edge of the keyboard case, a rocker arm fastened to said slider, a pair of levers connected to the ends of said rocker arm and means for actuating either of said levers and rocker arm by the presser bar whereby the slider may be shifted.

7. In an accordion having a pitch slider,

a plate attached to the bottom of the key-board case, a presser bar and spring hinges connecting said bar and plate, said presser bar being located at the front edge of the key-board, a rocker arm fastened to said slider, 5 a pair of angularly disposed levers connected to the ends of said rocker arm, said levers having notches and a post operable by a presser bar and adapted to engage a notch in either of said levers whereby the rocker arm and slider may be shifted.

8. In an accordion having a pitch slider, a presser bar attached to the bottom of the key-board case and in parallelism with the front 10 edge thereof, a rocker arm and a sliding rod connected to said rocker arm, a crank rod for operating the slider by the sliding rod, and means connecting the rocker arm and sliding rod for shifting the same laterally by said 15 presser bar.

20 In testimony whereof we affix our signatures.

EUGENIO GALIZI.
